UNITED STATES PATENT OFFICE.

PETER F. GALLAGHER, OF BALTIMORE, MARYLAND, ASSIGNOR OF FORTY-NINE ONE-HUNDREDTHS TO PHILIP CONNIFF, OF BALTIMORE, MARYLAND.

MEANS FOR CONNECTING SUPERHEATER-FLUES TO FLUE-SHEETS OF LOCOMOTIVES.

1,122,900.

Specification of Letters Patent.

Patented Dec. 29, 1914.

Application filed March 28, 1914. Serial No. 827,946.

To all whom it may concern:

Be it known that I, PETER F. GALLAGHER, a citizen of the United States, residing at Baltimore, State of Maryland, have invented certain new and useful Improvements in Means for Connecting Superheater-Flues to Flue-Sheets of Locomotives; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in means for connecting superheater flues to superheater flue sheets of locomotives, the object in view being to make a connection without impairing the efficiency or strength of the sheet and comprises essentially the offsetting and reinforcing of the margin of the opening in the flue sheet by forming an integral flange within which the flue is fastened and in the provision of a circular flexible corrugation about the flange in order to compensate for expansion and contraction of the metal, affording a greater degree of flexibility of the flue sheet.

Another and an important feature of the present invention consists in the provision of a circular corrugation about an integral flanged opening in which the flue is fastened and whereby the flue receiving flanges are offset beyond the surface of the flue sheet on the water side to protect the flues from the intense heat of the flames on the fire side.

Still another and important feature of the invention is the provision of means for welding the ends of the flues to the flanges in such a manner as to secure increased strength of connection and maximum security against breakage or leakage at the joint.

My invention comprises various details of construction and combinations and arrangements of parts which will be hereinafter fully described, shown in the accompanying drawing and then specifically defined in the appended claims.

My invention is illustrated in the accompanying drawings, in which:

Figure 1 is a side elevation of a portion of a flue sheet, showing two of the flue openings and flues, and illustrating clearly the connection of the flues with the sheet. Fig. 2 is a sectional view through the parts shown in Fig. 1, taken on a horizontal line through the center of the flues.

Reference now being had to the details of the drawings by letter, A designates a superheater flue sheet of a locomotive, said sheet having a series of flue receiving openings B about or in line with which are arranged the circular flanges C which receive the ends of the superheater flues D. These flues inclose the ordinary superheater pipes or units, as will be readily understood. These flanges are integral with and are punched from the material of the sheet, as shown. Each flange B is internally of true circular form and of proper diameter to fully receive and inclose the end of the flue, the flange thus being substantially throughout its length in contact with the end of the flue to support the latter to a maximum degree. About each flange is a circular corrugation E of a sufficient depth to form a groove or channel on the water side of the sheet for the circulation of water about the end of the flue, as will be readily understood by reference to Fig. 2. This corrugation is integral with the body of the sheet and joints the base of the flange to the sheet, and thus forms a reinforcing and connecting medium between the flange and sheet. As shown, the outer end of each flange is welded to the flue sheet therein, as indicated at C' in Fig. 2, while the inner end of each flue projects into the flue opening and is welded to the flange and wall of the opening, as indicated at D'. At this point of intersection of the flange and flue wall, the said parts are flared to provide a space between the same and the projecting end of the flue to snugly receive a welding filler of angular (triangular) form, as clearly shown in Fig. 2 whereby the joint is further strengthened and rendered proof against leakage. To further securely hold the flue to the flange, suitable fastening means may be used, such as tapering screws

F passing through registering threaded apertures in the wall of the flue and the flange, but the use of these or analogous fastenings is not essential.

5 The flues D are what are commonly known as "superheater flues", designed to receive the superheater pipes or units in locomotives of the superheater class, wherein the steam is superheated to a high degree 10 and the flue joints must stand a working pressure of from 190 to 225 pounds per square inch of boiler surface and a temperature of approximately 612° Fahr. As such flues are comparatively long, weighty 15 and of large diameter, and subjected with the flue sheets to intense temperatures and pressures at the joints, great difficulty is experienced in preventing cracking or warping of the flue sheets and cracking or leakage of the flues at their points of connection with the sheets. In addition to the factors of high and variable degrees of expansion and contraction, which tend to warp and disrupt the parts, a further difficulty is experienced in the pressures brought to bear 20 against the sheets and ends of the tubes by the bending and depression of the tubes under their own weight when they are not floating in and supported by the body of 25 water in the boiler, as when the water is removed in washing out or repairing the boiler, resulting in an up and down motion which tends to cause breakage or leakage at the joints. My invention is designed to 30 overcome all of these objections and to provide a flue connection which will be absolutely fluid tight and of proper strength and durability, as well as flexibility, to support the weight of the flue and to permit it 35 to expand and contract with the flue sheet without breaking or cracking the parts or causing leakage at the joints. By punching each flange C out of the material of the sheet, an integral support for the end of the 40 flue is furnished which does away with insecure connections and added parts liable to cause weakness or leakage. By connecting each of these flues with the material of the sheet by an interposed circular corrugation, 45 which corrugation is offset on the water side beyond the plane of the sheet, the sheet and flue are given increased strength and flexibility at the point of connection, while the sheet as a whole is rendered stronger and 50 more flexible to compensate for and withstand the pressures and strains to which it is subjected. The corrugation also brings the flange and flue end outwardly beyond the plane of the fire side of the sheet, so as to be 55 out of the direct fire line and to form an angular channel or recess about the flue and corrugation on the water side of the sheet, by which the aforesaid parts are better protected against the heat of the flange. By 60 the structure described the end of the flue, 65

while fully inserted within the flange, lies within a recess or depression in the flue sheet, whereby the end of the flue and its seat flange are offset from the fire line, thus preventing them from becoming unduly heated and unduly expanding and contracting or cracking.

By flaring the flange and wall of the flue opening at their point of intersection an angular recess is provided between said wall and the end of the flue which permits of the interposition of a welding filler whereby the surfaces may be homogeneously united and connection obtained which is absolutely proof against leakage while uniting the elements against any possibility of separation.

The advantages of the invention in preventing buckling, cracking or leakage, and in extending the life and efficiency of the boiler, will be readily understood and appreciated from the foregoing description.

What I claim to be new is:

1. A flue sheet having an opening therein, a circular flue receiving flange, and a corrugation about the base of said flange and joining the same to the flue sheet.

2. A flue sheet having an opening therein, a circular flue receiving flange, and a corrugation about the base of said flange and joining the same to the flue sheet, said flange and corrugation being offset from the plane of the flue sheet.

3. A flue sheet having an opening therein, a circular flue receiving flange, and a corrugation about the base of said flange and joining the same to the flue sheet, said corrugation being internally flared to form with the inserted end of the flue a weld filler receiving angle between said corrugation and the end of the flue.

4. A flue sheet having an opening therein, a circular flue receiving flange, and a corrugation pressed with said flange out of the material of the flue sheet and joining said flange at its base to the body of the sheet, said flange and corrugation being offset from the plane of the sheet.

5. A flue sheet having an opening therein, a circular flange, a corrugation pressed with the flange out of the sheet and joining said flange at its base to the sheet, said flange and corrugation being offset from the plane of the sheet and said corrugation flared at its junction with the flange, a tube having its end inserted through the flange and projecting into the flared portion of the corrugation to provide an intervening angular recess, and a filler inserted into said recess and welded to the corrugation and projecting end of the tube.

6. In a superheater flue connection, a flue sheet having a flue opening therein, a cylindrical flange in line with the opening, a circular corrugation connecting the flange with the wall of the opening and offset

from the plane of the sheet, said flange and corrugation being internally flared, a flue having its end extending through said flange and terminating in line with said flared portion to provide a recess, and a welding filler inserted in said recess and uniting the aforesaid parts.

In testimony whereof I hereunto affix my signature in presence of two witnesses.

PETER F. GALLAGHER.
